UNITED STATES PATENT AND TRADEMARK OFFICE
Certificate

Patent No. D657,216 S

Patented: April 10, 2012

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Anthony Kriz, Lone Tree, CO (US); Brent Christopher, Portland, OR (US); Mark Holtan, Centennial, CO (US); and YaoKun Gui, Shanghai (CN).

Signed and Sealed this Seventeenth Day of July 2012.

Robert M. Spear
Supervisory Patent Examiner

UNITED STATES PATENT AND TRADEMARK OFFICE
CERTIFICATE OF CORRECTION

PATENT NO. : D657,216 S
APPLICATION NO. : 29/392630
DATED : April 10, 2012
INVENTOR(S) : Anthony Kriz et al.

Page 1 of 1

It is certified that error appears in the above-identified patent and that said Letters Patent is hereby corrected as shown below:

On the Title Page

Item (73) the Assignee should read: "Meridian International Co., Ltd."

Signed and Sealed this
First Day of October, 2013

Teresa Stanek Rea
Deputy Director of the United States Patent and Trademark Office
